UNITED STATES PATENT OFFICE

2,295,677

MACHINE FOR OPERATING ON SHOE
UPPERS

Vernon H. Meyer, Beverly, Mass., assignor to
United Shoe Machinery Corporation, Flemington, N. J., a corporation of New Jersey

Application June 13, 1941, Serial No. 397,831

14 Claims. (Cl. 12—97)

This invention relates to machines for acting upon the bottoms of shoe uppers and more particularly to machines for forming an attaching flange on the back parts of shoe uppers.

In the manufacture of certain types of shoes, the bottom margin of the upper is turned inwardly to form an attaching flange around the back part prior to assembly of the upper with an insole. One example of such a shoe is illustrated in Letters Patent of the United States, No. 2,212,514, granted August 27, 1940, upon an application filed in the name of Karl Engel. In a shoe of the type illustrated by this patent, a sole is provided, the upper surface of which has a marginal channel bounded by a shoulder, and the inturned portion of the upper is positioned in the channel with the edge of the inturned portion abutting the shoulder. The upper is attached to the sole by suitable means, such as stitching passing through the inturned portion of the upper and the sole. In order that the upper may be properly assembled with the sole, the inturned marginal portion should have a contour similar to that of the shoulder of the channel in the sole. This is particularly true at the back part of the upper which is preferably pre-molded substantially to final shape, the back part being reinforced by a counter stiffener so that the flange formed at the bottom thereof is substantially non-yielding. Accordingly, the assembly of the back part to a sole of the type shown in the Engel patent may be very difficult if the flange does not conform to the shoulder on the sole.

It is an object of this invention to provide a machine having means for turning in the bottom margin to form an attaching flange and means for subsequently trimming the flange to a predetermined contour, thereby to facilitate subsequent shoemaking operations. To this end and as a feature of the invention, the machine herein illustrated has means for molding the back part of a shoe upper substantially to final shape, means for turning in the lasting margin to form an attaching flange, and a knife operative after the flange has been formed to trim the edge of the flange to a predetermined contour. Following the trimming operation, the flange may be pressed or molded to set the materials comprising the back part, after which the back part may be removed from the machine and assembled to a sole such as that shown by the Engel patent, although it should be understood that this invention is not limited to the manufacture of shoes of the type shown by that patent.

This and other features of the invention will

now be described in detail and illustrated in the drawings, wherein

Fig. 1 is an elevation, partly in section, of the head of a machine embodying the present invention;

Fig. 2 is a plan view, partly in section, illustrating certain parts of the machine in the positions assumed after the back part has been molded but prior to the flanging operation;

Fig. 3 is a vertical section on the line III—III of Fig. 2;

Fig. 4 is a fragmentary plan view, partly in section, illustrating the wiper plate after it has started its movement from the position of Fig. 2 to turn in the lower marginal portion of the upper, thereby to form a flange;

Fig. 5 is a plan view, partly in section, illustrating the wiper plate after it has completed its movement to form the flange and showing the knife slide in cross section;

Fig. 6 is a vertical section on the line VI—VI of Fig. 5, illustrating the knife in the process of trimming the previously formed flange;

Fig. 7 is a view, similar to Fig. 6, showing the knife at the completion of its trimming movement and the knife slide acting against the wiper plate to exert final molding pressure on the flange; and

Fig. 8 is a view of the back part on the inner mold at the completion of operation thereon by the machine, illustrating the trimmed flange.

The invention is illustrated as embodied in a machine of the type illustrated in application Serial No. 320,391, filed February 23, 1940, in the name of Karl Engel. This machine comprises a frame 10, to the front wall of which is secured a bracket 12 having an upwardly and rearwardly inclined surface forming the slideway for a slide 14, to the forward portion of which is secured an L-shaped support 16. An inner form or mold 18 is secured to the support 16 and is arranged to carry the back part of a shoe upper, the toe end of which is held by a gripper 20 mounted on a housing 22 extending upwardly from the bracket 12 and fixed thereto. Side grippers 24 carried by the support 16 engage the sides of the upper mounted on the form 18, these grippers 20 and 24 being shown in detail in the aforementioned Engel application. Upon movement of the slide 14 upwardly in the bracket 12, the form 18 moves away from the toe gripper 20, thereby to stretch the upper around the form 18. This form, as illustrated more clearly in Figs. 3 and 4, is shaped substantially like the heel portion of a last and

cooperates with a pair of outer molds 26 to mold the back part substantially to final shape.

The outer molds are slidably mounted in the upper portion of the frame 10 and are arranged to be moved toward one another and toward the form 18 by a lever 28 pivoted on a shaft 30, the upper end of the lever being connected by a link 32 to the outer molds in a manner more fully disclosed in the Engel application. The lower end of the lever 28 carries a cam roll 34 held by a spring 36 in engagement with a cam 38 mounted on a drive shaft 39 so that, upon rotation of the cam in a clockwise direction, the lever will be moved in a counterclockwise direction to bring the outer molds downwardly and inwardly toward the inner form 18. The inner form is simultaneously moved toward the outer molds upon rotation of the cam 38 to stretch the back part over the form. For this purpose the slide 14 is connected by a link 40 to a lever 42 pivoted to the frame at 44, the lever being in turn connected by a link 46 to the lever 28. As the lever 28 is moved in a counterclockwise direction, the lever 42 will be moved in a clockwise direction to move the slide 14 upwardly and carry the form 18 toward the outer molds 26.

After the upper has thus been stretched over the form 18 and molded between the form and the outer molds 26, the lasting margin of the upper which extends above the molds 26, as indicated in Fig. 3, is wiped inwardly to form a heel seat flange. This is accomplished by the movement of a wiper plate 50 forwardly (to the left, as shown in Fig. 1) over the upper surface of the form 18. This wiper plate is carried by a slide 52 mounted between plates 54 (Fig. 2) which are pivoted to a shaft 56 in the frame of the machine so that the plates and the slide may be moved upwardly as a unit at the completion of a flanging operation. Movement of the slide 52 to turn in the lasting margin is effected by clockwise movement of a lever 58 mounted on the shaft 30. The lower end of this lever carries a cam roll 60 held by a spring 62 against the periphery of a cam 64 mounted on the drive shaft 39. The upper end of the lever carries a block 66 slidable on a rod 68 extending from a member 69 pivoted at 70 to a link 72, which is in turn pivoted to a bracket 74 carried by the slide 52. A spring 76 is confined between the block 66 and the member 69, the block 66 being held against rearward displacement by nuts 78 threaded onto the rearward end of the rod 68. Upon clockwise rotation of the cam 64, the lever 58 will be moved in a counterclockwise direction and will act through the spring 76 to move the slide 52 forwardly, carrying with it the wiper plate 50 to turn in the flange over the adjacent surface of the form 18.

The forward portion of the wiper plate has a V-shaped notch 80, as shown in Fig. 4, the base of which is arranged to engage an upwardly extending boss 82 on the form 18 after the wiper plate has completed its wiping action, the boss 82 limiting movement of the wiper plate relative to the form so that it will stop in a predetermined relation thereto for a purpose which will appear hereinafter. The provision of the spring 76 between the lever 58 and the slide 52 carrying the wiper plate forms a yielding connection so that there will be no breakage of parts in the event that the cam roll 60 on the lever 58 does not reach the highest point on the cam 64 when the wiper plate moves into engagement with the boss 82.

The wiper plate is secured to the slide by screws 84, the holes in the wiper plate through which the screws pass being countersunk to receive springs 86 (Figs. 6 and 7) so that the wiper plate may be moved downwardly relative to the slide to press the wiped-in flange at a predetermined time during the operation of the machine, in a manner to be hereinafter described.

As shown more particularly in Figs. 2, 3, 6 and 7, the back part of the form 18 is recessed in its upper surface, the recess conforming in shape to the contour which the flange is ultimately to have. The walls of this recess form a shearing surface for a knife 88, which is generally U-shaped as shown in Fig. 4, this knife being movable through a correspondingly shaped aperture in the wiper plate 50. Upon downward movement of the knife through the wiper plate after the wiper plate has come to rest against the boss 82 on the form 18, those portions of the flange on the back part of the upper which overhang the edge of the recess in the form will be trimmed off, thus leaving the flange with a predetermined edge contour.

The knife 88 is secured by a screw 90 to a slide member 92 slidable in an upward extension 94 (Fig. 1) of the slide 52, the slide being provided with an opening 96 through which the slide member 92 passes. The lower end of the slide member has a flange 98 arranged to bear against the wiper plate 50 after the knife 88 has trimmed off the surplus material from the flange, as shown in Fig. 6, so that, upon further downward movement of the slide member 92, the wiper plate 50 will be moved downwardly relative to its slide member 52, thereby to compress and mold the materials of which the attaching flange is formed, namely the lining, counter stiffener and the upper leather.

The slide member 92, which carries the knife 88 and operates through the wiper plate to compress the flange, is connected by a link 100 (Fig. 1) to a lever 102 pivoted intermediate its ends to a pin 104 carried by the upward extension 94 of the slide 52. The rearward end of the lever 102 is provided with a longitudinal slot which slidably receives a block 106 carried by an arm 108 secured to a shaft 110 journaled in an upwardly extending bracket 112 at the upper end of the frame 10. The shaft 110 has also connected to it an arm 114, the lower end of which is pivoted to a rod 116 to which is yieldingly connected the upper end of an actuating arm 118 secured to the shaft 30. The shaft 30 has also connected to it an arm 120 carrying a cam roll 122 engaging the periphery of a cam 124 driven by the shaft 39. The slotted connection between the lever 102 and the arm 108 provides a lost motion connection to permit movement of the slide 52 forwardly to turn in the lasting margin, without causing any movement of the slide member 92 carrying the knife relative to the slide. However, after the slide 52 completes its movement and the flange has been wiped in, the cam 124 operating through the roll 122 and the arms 120, 118 causes movement of the rod 116 to the left, as viewed in Fig. 1. Thus the arms 114 and 108 move in a clockwise direction, lifting the right end of the lever 102 and causing downward movement of the slide member 92 to trim the flange and compress it, thereby imparting a permanent set to the materials forming the flange.

At the conclusion of a molding and flanging operation, the plates 54 are lifted about the shaft 56 by a cam 130, to lift the slide 52 and, with it,

the wiper plate and the slide member 92. This cam 130 acts through a cam roll 132 and a rod 134, the upper end of which is pivotally connected to one of the plates 54 (there being two sets of cams and cam rolls, one connected to each of the plates) to swing the entire assembly upwardly away from the back part, after which the molds are separated from the form 18 to permit removal of the back part from the machine.

The operation of the machine will now be reviewed. A shoe upper S, having a back part composed of outer leather U, lining L, and a counter stiffener C, is placed on the form 18, the toe end of the upper being held by the gripper 20 and the sides in the grippers 24. The shaft 39 is now rotated in a clockwise direction, whereupon the cam 38 causes the inner form and the outer molds to move together to stretch the upper over the inner form and mold the back part substantially into final shape. After the back part is thus molded, the slide 52 is moved forwardly, carrying the wiper plate 50 from the position shown in Fig. 2 into the position shown in Fig. 5, to turn in the lasting margin and form an attaching flange. The motion of the wiper plate is arrested by its engagement with the upwardly extending boss 82 on the form 18. The slide member 92 is then moved downwardly relative to the slide 52 carrying the wiper plate, whereupon the knife 88 carried thereby moves into the recess in the back part of the form 18 in shearing relation therewith to trim any portion of the flange which may overhang, thereby producing a flange having a predetermined contour. As shown in Figs. 5 and 6, the bottom of the recess in the form communicates with a passageway extending through the form so that the material trimmed by the knife may pass therethrough. Upon further downward movement of the slide 92 from the position of Fig. 6 to that of Fig. 7, the flange 98 carried thereby moves the wiper plate 50 downwardly against the force of the springs 86 to mold the trimmed flange and impart a final set to the materials.

It will thus be seen that, assuming the upper is to be assembled with a sole such as that shown and described in the above-mentioned Engel patent, if the knife 88 and the recess in the back part of the form 18 correspond in contour to the contour of the shoulder around the heel end of the sole, the flange produced by the apparatus will fit into the channel at the back part of the sole and abut the shoulder all the way around without any subsequent shaping of the back part, which would be very difficult inasmuch as the back part is premolded.

Having thus described my invention, what I claim as new and desire to secure by Letters Patent of the United States is:

1. In a machine for operating on shoe uppers, means for turning in a portion of the lasting margin to form an attaching flange, and means for trimming the in-turned flange to a predetermined contour.

2. In a machine for operating on shoe uppers, means for turning in a portion of the lasting margin to form an attaching flange, means for trimming the flange to a predetermined contour, and means for pressing the trimmed flange.

3. In a machine for operating on the back parts of shoe uppers, means for turning in the lasting margin to form a heel seat flange, and means for trimming the flange to a predetermined width.

4. In a machine for operating on the back parts of shoe uppers, means for turning in the lasting margin to form a heel seat flange, means for trimming the flange to a predetermined width, and means for pressing the flange.

5. In a machine for operating on the back parts of shoe uppers, a form shaped like the heel portion of a last, means for stretching the back part of a shoe upper over said form, means for turning in the lasting margin against the bottom of said form to produce a heel seat flange, and means for trimming said flange to a predetermined contour.

6. In a machine for operating on the back parts of shoe uppers, a form shaped like the heel portion of a last, means for stretching the back part of a shoe upper over said form, a wiper for turning in the lasting margin against the bottom of said form to produce a heel seat flange, means for trimming said flange to a predetermined contour, and means for pressing the flange against the bottom of said form.

7. In a machine for operating on the back parts of shoe uppers, an inner form shaped like the heel portion of a last, means for molding the back part of a shoe upper against said form, means for wiping in the lasting margin against the bottom of said form to produce a heel seat flange, and means cooperating with said form for trimming said flange to a predetermined contour.

8. In a machine for operating on the back parts of shoe uppers, an inner form shaped like the heel portion of a last, means for molding the back part of a shoe upper against said form, means for wiping in the lasting margin against the bottom of said form to produce a heel seat flange, means cooperating with said form for trimming said flange to a predetermined contour, and means associated with said wiping means for pressing the trimmed flange.

9. In a machine for operating on the back parts of shoe uppers, a form shaped like the heel portion of a last, means for shaping the back part of a shoe upper over said form, means for wiping in the lasting margin of the back part against the bottom of said form to produce an attaching flange, said form having a recess in the bottom thereof conforming in shape to the desired contour of said attaching flange, and a trimming knife movable into shearing relationship with the walls of said recess to trim said flange.

10. In a machine for operating on the back parts of shoe uppers, a form shaped like the heel portion of a last, means for shaping the back part of a shoe upper over said form, means for wiping in the lasting margin of the back part against the bottom of said form to produce an attaching flange, said form having a recess in the bottom thereof conforming in shape to the desired contour of said attaching flange, a trimming knife movable into shearing relationship with the walls of said recess to trim said flange, and means movable with said knife for pressing the flange after the edge thereof has been trimmed.

11. In a machine for operating on the back parts of shoe uppers, a form shaped like the heel portion of a last, means cooperating with said form for shaping the back part of a shoe upper, a slide movable in a plane parallel to the bottom of said form, a wiper carried by said plate for wiping in the lasting margin against the bottom of said form under light pressure to form an attaching flange, means urging said wiper toward

said slide, means movable toward the bottom of said form for trimming the flange so formed to a predetermined contour, and means for moving said wiper normal to said form to press the flange against the bottom of the form.

12. In a machine for operating on the back parts of shoe uppers, a form shaped like the heel portion of a last, means for stretching the back part of a shoe upper around the form, a wiper plate movable over the bottom of the form to produce an attaching flange, the central portion of said wiper plate having an aperture therein, means movable through said aperture for trimming said flange to a predetermined contour, and means operative against said wiper plate for 15 pressing the trimmed flange.

13. In a machine for operating on the back parts of shoe uppers, a form shaped like the heel portion of a last, means cooperating therewith to shape the back part of a shoe upper, the bottom of said form having a recess therein, a wiper plate movable over the bottom of said form to turn in the lasting margin and produce an attaching flange, said wiper plate having an aper-

ture therein registering with the recess in said form after the wiper plate has completed its flange-forming movement, and a knife movable through the aperture in said wiper plate and cooperating with the recess in said form for trimming the flange to a predetermined contour.

14. In a machine for operating on the back parts of shoe uppers, a form shaped like the heel portion of a last, means cooperating therewith to shape the back part of a shoe upper, the bottom of said form having a recess therein, a wiper plate movable over the bottom of said form to turn in the lasting margin and produce an attaching flange, said wiper plate having an aperture therein registering with the recess in said form after the wiper plate has completed its flange-forming movement, a knife movable through the aperture in said wiper plate and cooperating with the recess in said form for trimming the flange to a predetermined contour, and means including said wiper plate for pressing the flange at the conclusion of the trimming operation.

VERNON H. MEYER.
